UNITED STATES PATENT OFFICE.

THOMAS F. CRARY, OF MIDDLEPORT, OHIO, ASSIGNOR OF ONE-HALF TO CHARLES A. CRARY, OF MIDDLEPORT, OHIO

SOAP HOLDER.

Application filed June 2, 1924. Serial No. 717,351.

To all whom it may concern:

Be it known that I, THOMAS F. CRARY, a citizen of the United States, residing at Middleport, in the county of Meigs and State of Ohio, have invented a new and useful Soap Holder, of which the following is a specification.

This invention relates to a holder adapted to be applied to a cake of soap so as to render the cake buoyant.

A further object is to provide a holder which will not interfere with the use of the soap for toilet purposes and which will hold either a single cake of soap or several pieces of soap.

Another object is to combine with the holder a scrubbing surface whereby a desirable massaging action can be set up simultaneously with the application of the soap to the user.

At the present time certain soaps can be purchased which will float but these soaps are not as lasting and therefore not as desirable as the hard milled soaps which will not float. A floating soap is more desirable for toilet purposes, however, than a milled soap because it will not sink.

The present invention is designed for use in connection with hard milled soaps so that they will have all of the advantages of both a milled soap and a soft soap.

A still further object is to provide a holder which is cheap to manufacture and can be readily applied to a cake of soap.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown. In said drawings

Figure 1 is a view of one side of the holder.

Fig. 2 is a view of the other side thereof.

Fig. 3 is a section on line 3—3, Fig. 2.

Referring to the figures by characters of reference 1 designates a housing or casing formed of thin flexible rubber, this housing being shaped to fit snugly upon a cake of soap. Obviously the contour of the housing can be varied. The marginal portion of the housing is provided with a hollow rim 2 which is air tight and constitutes a float. One of the faces of the housing has an opening 3 sufficiently large to permit a cake of soap to be inserted therethrough into the housing, it being understood of course that the housing will stretch to any extent necessary to permit the insertion of the cake. Aperture 4 can be formed in either or both sides of the housing and if desired one of the sides can be provided with numerous spaced nipples 5 formed of rubber. Small openings 6 may be extended through these nipples and, if preferred, additional openings 7 can be located between them.

In using the soap holder a cake of soap is inserted through the opening 3 until properly seated within the housing. When the housing with the soap therein is placed in a body of water, the air contained within the rim 2 will render the same buoyant. By rubbing the housing over any portion of the body a lather will be produced by the soap and water and this will be applied to the body as efficiently as though the soap should be applied directly to the skin. By providing one face of the housing with the nipples 5, said face can be used as a scrubber for producing a massaging action.

Obviously various modifications of the structure can be made to meet the different requirements.

What is claimed is:—

A soap holder comprising a flexible housing having aperture through which the contents of the housing are exposed to the action of water, and a hollow rim carried by the housing for rendering said housing and its contents buoyant.

In testimony that I claim the foregoing as my own, I have hereto affixed my signature.

THOMAS F. CRARY.
